UNITED STATES PATENT OFFICE.

WILLIAM R. HILDEBRAND, OF NEW YORK, N. Y., ASSIGNOR TO PRINTING PRESS EXTENSION DELIVERY COMPANY, OF NEW YORK, N. Y., A CORPORATION OF NEW YORK.

PRINTING-PRESS ATTACHMENT.

1,358,152.

Specification of Letters Patent. Patented Nov. 9, 1920.

Application filed August 5, 1916. Serial No. 113,244.

To all whom it may concern:

Be it known that I, WILLIAM R. HILDEBRAND, citizen of the United States of America, residing at New York city, New York, have invented certain new and useful Improvements in Printing-Press Attachments, of which the following is a specification.

My invention relates generally to improved printing press attachments, and has more particular reference to a novel form of sheet collecting table and means for straightening sheets to be stacked on the collecting table.

15 In United States Letters Patent Number 1,104,669 issued to me on July 21, 1914, I have disclosed certain improvements in sheet collecting tables for printing presses, and the present invention is a development 20 of that cover by said Letters Patent.

One object of the invention is to provide means whereby the collecting table for the sheets shall be flexibly suspended, in such manner that the descending movement 25 thereof shall be exactly proportional to the thickness of the sheets fed thereto. By the provision of the novel means, hereinafter described, for causing the descent of the table I am enabled to secure extremely fine 30 adjustments properly proportional to the thickness of the sheets used at any given time.

A further object of the invention is to provide novel, and efficiently operative, means 35 for straightening the sheets as they are fed on to the table, so that as the sheets are superposed on the table they will form a perfectly straight stack with the sides all plumb.

40 Other objects and advantages of the invention, and its detail structure, will be disclosed in the following specification, reference being had to the accompanying drawing, in which—

45 Figure 1, is a side elevation of a printing press, having my improvements applied thereto;

Fig. 2, is a top plan view of the mechanism over the collecting table (the latter being omitted), this view showing particularly the means for straightening the sheets;

50 Fig. 3, is an enlarged detail perspective view of the mechanism for lowering the

sheet collecting table, as sheets are fed thereon; and

Fig. 4, is a perspective view of a special form of gear which I employ as part of the mechanism for lowering the table.

Referring to the drawings by reference characters, 10 denotes generally a printing press, which in the instance shown is of the type generally known as a cylinder press, although it is to be understood that my invention may be applied to other types of presses.

Extending forwardly from the press 10 is a pair of tracks 11, (only one of which is shown in the drawings), upon which the wheels or rollers of the grasshopper 12 travel. 13 denotes a set of tapes, as are usual in presses of this kind.

Projecting upwardly from the frame of the press is a head 14 in which bears a shaft 15, from which the grasshopper 12 is actuated. The shaft 15 is connected, by means 75 of a link 16, to one end of an extensible rod 17, the other end of which is connected to a moving part of the press, so as to be suitably thrust against at appropriate times. The construction so far described is common 80 to presses of the kind contemplated herein.

Adjacent the front end of the press, and below and supporting the forward part of the tracks 11, is an open frame which comprises the uprights 18, the lateral bars 19, 85 and the end members 20.

Each of the lateral bars 19 is provided with a series of perforated lugs or brackets 21, which form bearings in which shafts 22 are revolvably mounted. Each shaft 22 has a 90 plurality of pairs of spaced collars 23 keyed or otherwise secured thereon and between each such pair of collars is attached one end of a flexible cable, preferably wire rope 24. The other, pendent, end of each cable has an 95 eye 25 designed to engage a preferably S-shaped hook 26, said hooks being adapted to support cross bars 27, which are preferably formed as T-beams. Resting upon the broad faces of the T-beams 27, and removable therefrom, is the sheet collecting table or platform 28, which is in line with the open space of the frame 18—19—20.

At the rear end of each shaft 22, i. e., at the end adjacent the forward end of the 105 press, is loosely mounted a worm wheel 29

which meshes with a worm 30 carried on a shaft 31, extending at the rear end of the frame 18-19-20 at right angles to the axes of the shafts 22. Keyed to each shaft 22 adjacent each worm wheel 29 is a ratchet wheel 32 with which a pawl 33 co-operates. The pawl is pivoted to a lateral face of the worm wheel 29 and is held to its work by spring 34.

10 Carried loosely near one end of the shaft 31 is a sleeve 35 having a pendent arm 36 with a series of slots 37 therein, and also having an upwardly projecting arm 38, upon which is pivoted a pawl 39 designed 15 to coact with a ratchet wheel 40 keyed on the shaft 31.

Designed to engage any of the slots 37 is a pin 41 formed at one end of a rod 42, which projects rearwardly in the direction 20 of the press 10. It is desired that the rod 42 shall be longitudinally reciprocated at certain intervals, and to that end the rod 42 is operatively connected to a rod 43 which is driven from any suitable moving part of 25 the press, such as the gear wheel 44, said rod 43 being connected to the shaft 45 of the inking roller (not shown) which is rotated in the ink fount 46. The connection between rods 42 and 43 is effected by means 30 of a block 47 which is held by set screw 47^a on the rod 43, while the rod 42 passes loosely through the block and is capable of axial movement therein. The rod 42 is provided with spaced collars 48 at opposite sides of 35 the block 47, said collars receiving the impact of the block 47 whereby the rod 42 is moved back and forth.

At the end opposite that carrying the worm wheel 29 each shaft 22 is provided 40 with a hand wheel 49, to permit such shaft to be manually rotated, and for a like purpose the shaft 31 carries a hand wheel 50 at either end adjacent the sleeve 35.

Secured rigidly to either end of the shaft 45 15 is a crank arm 51, (only one of which appears in the drawing), said crank arms being pivotally connected at one end of long bars or links 52, which traverse the upper part of the frame 18-19-20. The opposite 50 ends of the links 52 are pivotally connected to bell crank levers 53, fulcrumed at 54 to lugs 55 carried by the side bars 19. The links 52 serve to support a transverse bar or "joggler" 56, which is adapted to strike 55 one edge of a sheet in the action of straightening the same during stacking.

Arranged opposite the bar 56 is a similar bar 57 against which the sheet strikes as it comes from the delivery mechanism of the 60 press. The bar 57 is supported by arms 58 secured at one end of rods 59, held in brackets 60 carried by the lateral frame members 19. At its ends the bar 56 has arms 58^a which are capable of sliding on 65 the rods 59, and said rods 52 have spaced

collars 61 at opposite sides of the bar 56 for striking against said bar and moving the same lengthwise.

One arm of each bell crank lever 53 has a forked end 62 engaging a pin 63 which projects from the enlarged portion of a rod 64 70 slidable in a sleeve 65. The rod 64 is normally pressed backwardly into the sleeve 65 by a coiled spring 66 and has secured to its projecting end a lateral bar or "joggler" 67 75 which extends at right angles to the bars 56 and 57, the bars 67 being adapted to act against the lateral edges of the sheets to strengthen them during stacking on the table 28.

80 The invention operates in the following manner:—It is desired that after a sheet of paper is laid on the table 28 the latter be lowered a distance corresponding exactly to the thickness of such sheet, so that the upper 85 face of the stack on the platform 28 shall be substantially flush at all times with the sheet delivery mechanism of the press. If, now, it be assumed, as is the case, that the space between any two teeth adjacent each 90 other on the ratchet wheel 40 corresponds to the thickness of the thinnest sheet of paper handled by the press, it follows that if such thinnest paper be used for a run the ratchet wheel 40 should be turned one tooth after 95 each sheet is laid on the table 28, so that the latter may descend a distance equal to the thickness of such sheet. In order that at each operation of the press the ratchet wheel 40 may be turned one tooth, the pin 100 41 is secured in the uppermost slot 37 of the arm 36. Thereafter, when the press operates, the rod 43 will be moved back and forth once during each rotation of the gear wheel 44, and owing to the connection 105 47-48 between rods 43 and 42 the latter will be correspondingly moved axially back and forth. In the backward movement there is some lost motion until the block 47 strikes the rear collar 48, and during this 110 period a sheet of paper from the press is laid on the table 28. When the block 47 strikes the rear collar 48 the rod 42 will be drawn backwardly revolving the sleeve 35 so that the pawl 39 will advance the ratchet 115 wheel 40 one tooth. The effect of this is to turn shafts 21 a proper distance to unwind cables 24 and suitably lower the platform 28. For different thicknesses of paper, to get a greater throw of the arm 36 and a correspondingly greater feeding thrust of the pawl 39, the block 47 is adjusted on the rod 43, and the pin 41 is placed in one of the other slots 37 in the arm 36, dependent 120 on the extent of rotation desired for the 125 ratchet wheel 40.

If it be desired to raise or lower the table 28 manually any of the wheels 49 or 50 may be turned in the proper direction, and these wheels are provided at both ends and sides 130

of the machine so that the operator need not go to any special part of the machine to actuate the table 28.

The sheet straightening mechanism, which 5 coöperates with the collecting table, is actuated once during each operation of the press. As a printed sheet is delivered from the press it strikes the rear bar 57 and may or may not remain properly positioned. As 10 the shaft 15 revolves it actuates the links 52 moving them forward and causing the rear collar 61 to advance the bar 56 against the rear edge of the sheet. Practically simultaneously with this motion of bar 56, the 15 bell crank levers 53 will force the side bars 67 toward each other thus straightening the lateral edges of the stack. As the links 52 retract the bars 56 and bars 57 will be moved back to initial positions in preparation for 20 the next straightening operation.

It will, of course, be understood that when the rod 42 is moved forward the pawl 39 will be retracted, gliding over the teeth of ratchet wheel 40 without operating the latter.

25 What I claim as new and desire to secure by Letters Patent is:—

In a sheet collecting means to be used in connection with a printing press and the delivery mechanism thereof, a pair of revolu- 0 ble shafts supported by said frame, cables

carried by said shafts, a counter shaft ex- 35 tends at right angles to the first named shafts and supported by the frame, a worm gear connection between the counter shaft and the first named shafts, whereby the first named shafts can only be rotated through the movement of the counter shaft, a sleeve on said counter shaft, said sleeve having a depending slotted arm and an upstanding arm, a bar having one of its ends adapted 40 to engage a slot in the depending arm, a second bar having one end connected to a moving part of the press, a block adjustable on one bar through which block the other passes, a pawl pivoted to said upstanding 45 arm, and a gear wheel on the counter shaft with which said pawl coöperates to intermittently rotate the counter shaft, the degree of arcuate movement of said counter shaft and the distance of the intermittent 50 lowering of the cables being predetermined by the location in the slot of the depending arm wherein the said first named bar is pivoted.

In testimony whereof I have affixed my 55 signature in presence of two witnesses.

WILLIAM R. HILDEBRAND.
